CONTAINER, MATERIALS AND PARTS
THEREFOR

Philip Zalkind, New York, N. Y.

Application March 14, 1942, Serial No. 434,649,
which is a division of application Serial No.
196,139, March 16, 1938. Divided and this ap-
plication February 18, 1944, Serial No. 522,853

1 Claim. (Cl. 24—204)

1 This invention is a division of my application Serial No. 434,649, filed March 14, 1942, which in turn is a division of my Patent No. 2,276,363, issued March 17, 1942. The invention described and claimed in this application relates to containers and parts thereof constructed from fibrous sheet materials and improvements therein, and more specifically relates to corrugated board, paper board, cardboard, felt cloth, paper material and other types of fibrous sheet material, methods of producing them and their use in connection with collapsible containers.

The present invention relates more specifically to means for securing together edges of sheet material, and has for its primary object the formation of a secure and safe fastening for containers, cartons and the like.

Another object of the present invention is the provision of a closure means for safety envelopes.

Other objects and uses of my invention will be apparent from the following description and drawings in which:

Figure 1 illustrates in plan view a modified form of edge formation for the purpose of uniting edges of plane sheets.

Figure 2 is a perspective view of the sheets of Figure 1 illustrating the manner in which the edges of the sheets may be brought together for the purpose of uniting such edges.

Figure 3 is a plan view of the sheets of Figure 1 after such sheets have been united along their edges.

Figure 4 is a view in cross-section of the sheets of Figure 3 taken on line 4—4 and looking in the direction of the arrows.

Figure 5 is a perspective view showing an alternative method by which the sheets of Figure 1 may be laid together for the purpose of uniting them at their edges.

Figure 6 is a cross sectional view which corresponds to Figure 4 and illustrates the formation of the uniting sheets of Figure 5.

Figure 7 is a plan view illustrating a modified form of the edge formation of Figure 1.

Figure 8 is a plan view of the sheets of Figure 7 after such sheets have been united along their edges.

Figure 9 is a plan view of the reverse side of Figures 3 and 8.

Figure 10 illustrates in plan view in modified form of the edge formation of Figure 1 for the purpose of uniting sheets at their edges.

Figure 11 is a plan view showing the sheets of Figure 10 united along their edges.

2

Figure 12 is a sectional view in perspective taken along the line 12—12 of Figure 11 and looking in the direction of the arrows.

In Figure 1, I have illustrated a preferred means by which a secure union may be obtained between edges of adjacent sheets or opposed edges of a single sheet. In the figure, sheets 300 and 300' are to be united at the edges 302 and 303. Each edge carries series of tongues 304 extending from such edge, which tongues may be integral with the sheet to be joined. Lugs 305 extend from the lateral edges of the tongues 304 and may be integral with such tongues. Preferably, the spaces between tongues will be equal to the width of said tongues, such space being, however, wholly or partly filled up by lugs 305, adjacent lugs being separated by a cut or slot 305a as expediency requires.

In order to unite the sheets 300 and 300' by means of the tongues and lugs, such sheets should be placed with respect to each other so that each tongue 304 on each sheet will lie exactly opposite the space defined by lugs 305 and slot 305a between tongues on the other sheet and thus lie opposite a pair of lugs 305. The edges 302 and 303 of the sheets 300 and 300' are then brought up in face to face relation to each other as shown in Figure 2, the tongues 304 are pushed beyond the lugs 305 on the opposed sheet so that each pair of lugs which originally were opposite a particular tongue of the opposed sheet engage behind said tongue and interlock with similar lugs extending from said tongue producing the condition shown in the plan view of Figure 3 in which it is seen that lugs 305' are caught behind tongues 304 and lugs 305 are caught behind tongues 304', the said lugs 305' and 305 interlocking with each other. In cross-section, the sheets thus joined will then present the appearance of Figure 4, edge 303 of sheet 300' overlapping and lying upon sheet 300, and the edge 302 of sheet 300 overlapping and lying upon sheet 300'.

Where the sheets to be thus united are of relatively stiff material, I have found it useful to provide score lines 306 between the tongues 304 and the remainder of the sheet and also to provide additional score lines 307 between the lugs 305 and their respective tongues 304 in order to facilitate the operation by which lugs of opposed sheets are interlocked with each other and behind opposed tongues.

In using my novel uniting means, it is not essential to bring the edges of the sheet up in face to face relation as in Figure 2. The sheets

3

may be laid so that the edges overlap as shown in Figure 5; the tongues 304 may then be pressed beyond the lugs 305 of the opposed sheet so that the lugs of opposed sheets are caught behind tongues and interlock with each other, producing a line of union which in cross-section presents the appearance of Figure 6; which, it will be noted, is exactly similar to the line of union of Figure 4 which was formed by turning up the edges of the sheets in face to face relation with each other (Fig. 2) before interlocking the lugs and tongues.

Various other methods of making use of the special formations herein shown will be obvious. Thus, the edges may be bent along the score lines 306 and turned up at approximately right angles so that edges of opposite sheets may be placed in face to face relation with each other and the lugs and tongues interlocked; the sheets thereafter being laid flat with the overlapping edges pressed down as shown in Figure 4. Or the sheets to be united may be laid upon each other so that the preformed edges coincide, the lugs and tongues may be pressed into interlocking relationship, and the sheets laid flat, again producing the cross-sectional appearance of Figure 4. Or the tongues and their associated lugs may have the formation shown in Figure 7, the tongue 314 being pointed, the lugs 315 nevertheless being capable of interlocking and being caught behind the tongues; in which case, the points of each tongue may be inserted in the cut 316 behind a pair of lugs and the sheets then pushed together to produce the united sheets of Figure 8. It should be noted that such pointed formation will also facilitate the joining of sheets by any of the other operations above described.

Although I have illustrated rectangular and pointed tongues and lugs, it is obvious that many other forms may be used within the spirit of my invention. Their relative dimensions may be varied and their shapes otherwise changed without departing from the novel means described.

In all cases, the tongues and lugs may, in the united sheets, be caused to appear on one side of such sheet only as seen in the plan view of Figures 3 and 8. The opposite surface of such united sheet may then be plane and unmarred as in Figure 9 showing along line 317 only the barest suggestion of the fact that the sheet had been joined along such line.

Such a joint, by the interlocking of lugs and tongues, will create a secure mechanical seal not dependent on tape, adhesive, mortising or other means now known in the art.

In addition, after the joint is formed, the overlapping and interlocking lugs and tongues may be adhesively attached to the subjacent sheet to prevent any intentional disruption of the joint. Where the sheets are compressible, as for instance corrugated board, the overlapping tongues and

4

lugs may be compressed together with the subjacent portions of the united sheets so that the entire sheet may be of uniform thickness, and adhesive tape may be placed over the joint for the purpose of improving the appearance.

This form of joint can be of exceptional usefulness in connection with "safety" envelopes and in the formation of "pilfer-proof" closures therefore. The edge of the flap of such an envelope and the free edge of the body of said envelope having the formation shown in Figures 1 or 7; the tongues and lugs being interlocked in the manner described in connection with Figure 5 so that the interlocking lugs and tongues will lie on the interior of the envelope thus presenting at such line of union an outer surface similar to that shown in Figure 9. Such envelope then cannot be opened without tearing the lugs or tongues and thus revealing the fact that the envelope had been tampered with.

In Figures 10, 11, and 12, I have shown a modification of the construction of Figures 1 to 9 inclusive, in which the sheets 350 and 351 (Figure 10) to be joined, have a mortised, indented, serrated, or broken edge producing tongues or extensions 352 separated by spaces 353. As will be seen more clearly from Figures 11 and 12, sheets 350 and 351 may be laid together edge to edge so that tongues or extensions 352 of each sheet enter the spaces 353 between the tongues of the opposite sheet, the edges of the two sheets being interlocked by the interlocking of the tongues 352, to produce a firm, strong line of union. The interlocked tongues 352 may then be glued down upon the sheets on which they rest, they may be wholly or partially compressed into the body of the sheet upon which they rest to produce a level surface, and/or a strip of tape may be adhesively affixed over the line of union formed by the tongues 352 wholly or partially covering the tongues and maintaining the predetermined desired relation between them.

Having now described my invention, I claim:

A formation for the edge of a sheet of fibrous material for joining such edge to a similarly formed edge; such formation comprising tongues extending from such edge and lugs extending from the side edges of said tongues, the tongues of the similarly formed edge being juxtaposed opposite the lugs of the first edge, the lugs of each edge being foldable to pass between the tongues of the opposite edge and being thereafter arrangementable to extend in surface to surface relation behind said tongues, the tongues in each edge being substantially equal in width to the spaces between the tongues; the lugs substantially filling said spaces, said tongues being substantially triangular in shape; said lugs comprising portions of said triangular tongues.

PHILIP ZALKIND.
